UNITED STATES PATENT OFFICE.

LEOPOLD STIASSNY, OF NEW YORK, N. Y.

INCANDESCENT-MANTLE SUPPORT.

SPECIFICATION forming part of Letters Patent No. 611,527, dated September 27, 1898.

Application filed February 24, 1898. Serial No. 671,514. (No model.)

To all whom it may concern:

Be it known that I, LEOPOLD STIASSNY, a subject of the Emperor of Austria-Hungary, residing at New York, in the county and State 5 of New York, have invented new and useful Improvements in Mounting Incandescent Mantles, of which the following is a specification.

By means of this invention mantles for incandescent lighting can be readily mounted, as set forth in the following specification and claims, and illustrated in the annexed drawings, in which—

Figure 1 is a sectional elevation of a mantle and support. Fig. 2 is a sectional elevation at right angles to Fig. 1. Fig. 3 is a section along line $\alpha\alpha$, Fig. 2. Fig. 4 is a plan view of Fig. 2. Fig. 5 shows a modification. Figs. 6 and 7 show another modification.

20 A mantle-carrying ring or tube 1, of suitable metal or material, has the mantle 2 suitably closed or secured thereabout, as by a wire or suitable string 3, run or stitched through the upper edge part of the mantle and tied or drawn about ring 1. This ring or setting 1 is provided with supporting-arms 4, which are secured to the main carrier or ring 5, having leg or standard 6. The arms 4 are suitably secured to carrier 5. A quick manner of securing is attained by bending or hooking arms 4 to or about ring 5, although wiring or other fastening means might be employed.

The mantle-carrying ring 1 could be formed integral with arms 4 or otherwise secured thereto. In the drawings the upper part or edge of ring 1 is shown flanged or bent at 7 over a ring 8, seated about ring 1 and forming part of or connected to arms 4. The ring 8 being slipped about or seated on the shoulder 9 of ring 1 and the edge 7 of ring 1 being then flanged over ring 8, the parts are secured together.

The attaching of the mantle-carrying ring 1 to arms 4 and of the latter to the main carrier 5 can be readily effected and does not necessitate handling of the mantle 1. In consequence of the comparative frailty of the mantle the handling of the latter is objectionable.

In Fig. 5 the tube or setting 1 is shown provided with a flange or flaring piece 10, which is suitably flanged or connected to or formed

on the lower part of tube 1 and prevents mantle 2 from slipping down or falling out of place. By suitably rounding edge 11 of the piece 10 the latter is prevented from cutting or injuring the mantle. A washer or ring 12 can also be applied or seated under arms 4 and will serve to keep the mantle from slipping up or out of place. The washer 12 can be omitted, if seen fit. The parts 1, 4, as also flare 10, together with washer 12, if used, could be formed of one or of several pieces of metal, as found desirable. The flare 10 can be made of open or perforated or transparent work, if seen fit.

25 The main carrier or ring 5 can be filed or dented, as at 13, Fig. 4, so as to give depressions or seats in which arms 4 can swing to allow the mantle certain freedom of motion.

The mantle-carrying ring or setting 1 or its ring 8 need not have the support 4 in the form 70 of arms, since a modified form of support, such as bail 4', Figs. 6 and 7, will sustain the mantle. When the support 4' is placed in the seat or hook 13' of main carrier 5', the support 4' is 75 swingingly sustained in such seat or depression 13'.

What I claim as new, and desire to secure by Letters Patent, is—

1. The combination with supporting-arms having a ring, of a mantle-carrying ring 80 flanged about the first-named ring substantially as described.

2. The combination with supporting-arms having a ring, of a mantle-carrying ring having a shoulder for the support of and flanged 85 about said first-named ring, and a main carrier about which the arms are bent substantially as described.

3. A mantle-carrying ring provided with two horizontal arms extending radially in opposite directions, in combination with a supporting-ring provided with depressions at its opposite sides, the ends of said arms being bent around the depressed portions of said supporting-ring, substantially as described. 95

In testimony whereof I have hereunto set my hand in the presence of two subscribing witnesses.

LEOPOLD STIASSNY.
